WALKING SKATE SHOE

Max Smoker, New Paris, Ind.

Application February 2, 1938, Serial No. 188,324

2 Claims. (Cl. 280—11.38)

This invention relates to means to permit a person to walk around with skates attached to his shoes without having to walk directly on the runner of the skate, or bring the runner of the skate into contact with a floor or the ground until the person reaches the ice.

An important advantage of the invention is to provide a device that can actually be walked upon and which will permit the skater to put on his skates inside a building where it is warm and then attach the shoe to the skates or to the feet so that the skater may then walk out of the building to the ice in comfort and there remove the protecting shoe. A further primary object of the invention is to protect the skate runner against damage in walking over gravel, floors, and the like.

These and other objects and advantages of the invention will become apparent in the following description of one particular form of the invention which is illustrated in the accompanying drawing, in which

Fig. 1 is a side elevation of a structure embodying the invention;

Fig. 2, a top plan view of the shoe;

Fig. 3 a longitudinal central vertical section on the line 3—3 in Fig. 2; and

Fig. 4, a transverse vertical section on the line 4—4 in Fig. 2.

Like characters of reference indicate like parts throughout the several views in the drawing.

I form a shoe out of any suitable material such as rubber, metal, plastic molded materials, wood, or the like. In the form herein shown as one particular example, the shoe is made out of wood and is generally designated by the numeral 10.

This shoe 10 is made to have a central longitudinal slot or groove 11 across its top side in which the runner 12 of a skate may be received. The shoe is made to have a length at least equal to the length of the runner 12 and preferably longer as indicated in Fig. 1 wherein the shoe will extend beyond the front and rear ends of the skate runner 12 of a skate may be received. The rear end of the groove 11 terminates a slight distance from the rear end of the shoe as indicated in Fig. 3, herein shown as by an upwardly inclined floor of the groove. A metal plate 13 is secured across the top side of the shoe 10 immediately over the rear end of the groove 11 to serve as an abutment for the rear end of the skate runner.

The under side of the shoe 10 is shaped to have a heel 14 and a sole or ball part 15 ahead of the heel. Preferably the heel 14 on the wood shoe

is placed to be directly under the heel of the shoe 16 of the skater and the shoe is sloped upwardly and rearwardly from this heel part so as to permit greater ease in walking and prevent interference with the ground as the foot swings the 5 shoe along in natural walking. Likewise the forward under side of the shoe 10 is sloped upwardly to the front or tip end. The portion between the heel 14 and the ball 15 is cut away as best indicated in Figs. 1 and 3. The shoe is given a sufficient width as to provide stability in walking so as to prevent strain or twisting action on the ankles of the skater in walking about.

The shoe 10 is secured in position on the skater's foot by means of a toe strap 17 having ends secured to the shoe 10, herein shown as on the sides of the shoe directly under the toe of the skater's shoe 16. This strap 17 is preferably provided in two parts to be drawn up snugly by means of the usual buckle engagement 18. A rear strap 19 is 20 also provided to extend forwardly from the sides of the heel 14 of the skate shoe 10 and extends upwardly over the instep of the skater's shoe 16 immediately ahead of his ankle as best indicated in Fig. 1 whereby the skate shoe is tended to be 25 drawn forwardly to maintain the rear end of the 10 skate runner 12 in firm abutment with the metal bar 13. The upwardly inclined end of the floor of the groove 11 also aids in wedging the skate runner into firm engagement with the shoe in junction with the pull of the straps 19 and 17.

Thus it is to be seen that I have produced a very simple and yet highly satisfactory means for permitting the skater to walk about off the ice in comfort and without danger of damaging the 35 skates. Furthermore it is to be seen that this skate shoe may be produced and sold at a relatively low cost so as to bring the use of the shoe 30 within the range of the ordinary skater.

While I have herein shown and described my 40 invention in the one particular form, it is entirely obvious that structural changes may be employed without departing from the spirit of the invention and I therefore do not desire to be limited to that precise form beyond the limitations as 45 may be imposed by the following claims.

I claim:

1. For a skater, a skate shoe comprising a body having a central longitudinal groove to receive therein the runner of a skate, the body having 50 under heel and ball portions wider than the skate runner for ground contact, said heel portion having a rear extension beyond the heel of the skater sloped upwardly and rearwardly from the level of the heel portion to the top of the tip end of the 55

extension, and releasable means for drawing the shoe upwardly snugly against the skate runner, whereby the skater may walk about on the skate shoe with the skate protected thereby.

5 2. For a skater, a skate shoe comprising a body having a central longitudinal groove to receive therein the runner of a skate, the body having under heel and ball portions wider than the skate runner for ground contact, and releasable means
10 for drawing the shoe upwardly snugly against the skate runner, whereby the skater may walk about on the skate shoe with the skate protected there-

by, said heel portion having a rear extension beyond the heel of the skater sloped upwardly and rearwardly from the level at the heel portion to the top of the tip end of the extension and the front end of the body having an extension beyond the shoe sloped upwardly from the ball to the tip end of that extension, said groove being limited in width to receive therein said runner with a close sliding fit to prevent lateral rocking of the shoe about the runner.

MAX SMOKER.
